DEMOUNTABLE TRUCK BODY FOR RAILROAD TRANSPORTATION

Filed March 7, 1939

FIG. I.

A technical line drawing of a mechanical assembly. At the top, a large, thin-walled rectangular component is shown. Below it, a horizontal beam is supported by two vertical cylindrical components, labeled 16. A central horizontal assembly, labeled 18, is attached to the beam. The entire assembly is mounted on a base. There are also two additional vertical cylindrical components on the base, one on each side of the central assembly. The drawing includes several reference numerals: 15 at the top left, 16 on the right side, 18 on the central horizontal beam, and 5A in a box at the top right.

DEMOUNTABLE TRUCK BODY FOR
RAILROAD TRANSPORTATION

José G. Valenzuela, Mexico City, D. F., Mexico

Application March 7, 1939, Serial No. 260,387
In Mexico June 30, 1938

3 Claims. (Cl. 105—366)

This invention relates to demountable truck bodies for railroad transportation and more particularly to a body adapted for use in carrying less than a carload load.

5 An object of this invention is to provide a container and means for supporting the container in a railroad car so that material may be placed in the container and the container sealed in order that the material in the container may be left sealed therein during the entire shipment of the material, and the container is so constructed as to be readily mountable on a truck chassis so that it may be readily carried to and from the railroad in addition to being transported within a railroad car without opening the container.

10 Another object of the invention is to provide a less than a carload container which includes means for facilitating the positioning of the container within the railroad car and also means for locking the container against movement relative to the railroad car.

15 A further object of this invention is to provide the combination with a railroad car of less than a carload container and means within the railroad car for positioning the container in the desired position within the car.

20 To the above objects and to others which may hereinafter appear, the invention consists of the novel construction, combination and arrangement of parts as will be more specifically referred to and illustrated in the accompanying drawing wherein is shown embodiments of the invention, but it is to be understood that changes, variations 25 and modifications may be resorted to which fall within the scope of the invention as claimed.

In the drawing:

25 Figure 1 is a detail side elevation partly broken away and in section of a container constructed according to an embodiment of this invention mounted on a truck chassis which is shown in fragmentary form.

30 Figure 2 is a detail end elevation of the truck chassis with the container mounted thereon,

35 Figure 3 is an enlarged sectional view taken on the line 3—3 of Figure 1.

40 Figure 4 is a fragmentary sectional view taken on the line 4—4 of Figure 3.

45 Figure 5 is an enlarged fragmentary sectional view taken on the line 5—5 of Figure 1.

50 Figure 6 is a view similar to Figure 5, but showing the locking means in released position.

55 Figure 7 is a fragmentary sectional view taken on the line 7—7 of Figure 6, and

Figure 8 is a fragmentary sectional view taken on the line 8—8 of Figure 5.

Referring to the drawing, and first to Figures 1 to 8 inclusive, the numeral 15 designates generally a container which is adapted to hold articles for shipment, and in the present instance, the container 15 is adapted to be of a size to occupy substantially all of the space between the floor and the top of the railroad car, but is of a length less than the length of the railroad car so that a number of these containers 15 may be positioned within the railroad car. The container 15 is provided with a plurality of transversely extending beams 16 which are secured to the bottom thereof and a pair of U-shaped slide members 17. The slide members 17 open at the bottom thereof and slidably engage over a pair of parallel beams or rails 18 which may be secured to the floor of the railroad car and which may also be secured to the chassis of a motor vehicle truck.

5 The channel members 17 are provided at spaced intervals along the bight 19 thereof with a plurality of rollers 20 which are carried by bearings 21 and these rollers 20 project partly through openings 22 provided in the bight 19 so that the rollers 20 will contact with the upper surface of the beams or rails 18. In order to provide a means whereby the correct position of the container 15 may be readily determined when the container is placed in a car or on a truck, the beams 18 are provided with concave recesses or roller seats 23. There is a seat 23 for each roller 20 and when the body or container 15 is in the desired location all of the rollers 20 will be seated in a recess 23 so that the channel members 17 will rest substantially entirely upon the beams 18.

10 The rollers 20 provide a means whereby the containers 15 are held against longitudinal or endwise movement on the rails 18, but in order to lock the containers 15 against movement on the rails or beams 18, I have provided a plurality of locking members comprising a locking rod 24 which is carried by a housing generally designated 25. The rod 24 at its inner end is adapted to engage in a socket or keeper 26 which is provided in the side of a rail or beam 18 and these keepers 25 are correlated with the recesses 23 so that when the container 15 is positioned with all of the rollers 20 in their associated recesses 23, the locking bolts 24 will be positioned in a confronting position relative to a keeper 26. The housing 25 comprises a hollow body 27 provided with a flange 28 which is adapted to be secured as by 50 55

fastening members 29 to one side 30 of the U-shaped member 17. The housing 25 is provided with a reduced outwardly tapering extension 31 through which the locking bolt 24 slidably engages. The side or leg 30 of the channel member 17 is provided with a bolt guide opening 32 which registers with the opening 33 provided in the outer wall 34 of the extension 31. The bolt 24 at its outer end is provided with a looped handle 35 and when the bolt 24 is in a locked position, the inner portion of the handle 25 is adapted to seat in a U-shaped seat 36 carried by the outer wall 34 of the extension 31.

The housing 25 at the inner end of the extension 31 is provided with a pair of inwardly projecting lugs 37 and the bolt 24 has a disc-shaped plate 38 fixed thereto which is provided with a pair of diametrically opposed slots 39 which are adapted to be turned to register with the opposed lugs 37 so that the bolt holding plate 38 may be moved to a position shown in Figure 6 in which position the plate 38 is turned at right angles to the lugs 37 and the plate 38 is held against inward movement by the lugs 37. The plate 38 and the bolt 24 are constantly urged to a locking position by a spring 40 which is in the reduced housing 31 and at one end bears against the outer wall 34 of the housing 31 and at its inner end bears against the plate 38. The reduced housing 31 is preferably braced by a pair of bracing webs 42 which extend from the housing 31 to the outer portion of the housing 25.

It will be possible with a combination as disclosed in the drawing for shippers to seal the articles which are being shipped in containers and the consignees may remove the containers from the car in the original condition of the container. This will make it unnecessary for the railroad to handle the different articles which are being shipped as is at present the case, and in this manner the articles will arrive at their destination in substantially their original condition. In addition to this, the provision of less than carload containers similar to the containers hereinbefore described will facilitate the transportation of the articles to and from the railroad and will make it possible to eliminate various small sidings which are now necessary to remove the articles from the freight cars.

50 What I claim is:

1. In combination, a mobile structure, a pair of spaced parallel guide members within, disposed lengthwise of and fixed to said structure, a container, spaced parallel transversely extending beams secured to and depending from the bottom of the container, a pair of spaced parallel inverted U-shaped slide members disposed in lengthwise relation with respect to the bottom of the container, said slide members having their bights secured at spaced portions thereof to said beams, said slide members being disposed in depending relation with respect to said beams and each having its bight formed lengthwise thereof with spaced pairs of spaced openings, each of

said slide members having its bight seated on the top of and its sides opposing the sides of one of said guide members, a pair of spaced parallel bearings disposed on the top of the bights of the slide members at the sides of each opening in 5 a bight, a pair of spaced rollers mounted in each pair of spaced openings and each supported at its axis by a pair of said spaced bearings, said rollers having portions thereof spaced from their axes depending through said openings, and said 10 guide members having their upper surfaces formed with recesses for receiving the lower part of the depending portions of said rollers to thereby position said container relative to said structure. 15

2. In combination, a mobile structure, a pair of spaced parallel guide members within, disposed lengthwise of and fixed to said structure, a container, spaced parallel transversely extending beams secured to and depending from the 20 bottom of the container, a pair of spaced parallel inverted U-shaped slide members disposed in lengthwise relation with respect to the bottom of the container, said slide members having their bights secured at spaced portions thereof to said 25 beams, said slide members being disposed in depending relation with respect to said beams and each having its bight formed lengthwise thereof with spaced pairs of spaced openings, each of said slide members having its bight seated on 30 the top of and its sides opposing the sides of one of said guide members, a pair of spaced parallel bearings disposed on the top of the bights of the slide members at the sides of each opening in a bight, a pair of spaced rollers mounted in each 35 pair of spaced openings and each supported at its axis by a pair of said spaced bearings, said rollers having portions thereof spaced from their axes depending through said openings, and said guide members having their upper surfaces 40 formed with recesses for receiving the lower part of the depending portions of said rollers to thereby position said container relative to said structure, each of said beams having spaced portions arranged between rollers of said opposed 45 pairs of rollers.

3. In railroad transportation, a mobile structure, a pair of spaced parallel guide members within, disposed lengthwise of and fixed to said structure, said guide members having their outer 50 sides provided with spaced sockets, a mobile container for removably mounting on said guide members and having longitudinally extending depending parts for overlapping the outer sides of said members, said parts being formed with 55 openings for registry with said sockets, and a plurality of spaced latching structures secured to the outer side of each of said parts and including releasable spring controlled means normally extending through said openings into said 60 sockets for latching said container to said mobile structure.

JOSE G. VALENZUELA.
